UNITED STATES PATENT OFFICE.

ARCHIE W. STEELE, OF BLOOMFIELD, NEW JERSEY, ASSIGNOR TO WILFORD J. HAWKINS, OF MONTCLAIR, NEW JERSEY.

ELECTRIC FUSE.

Application filed December 3, 1919. Serial No. 342,225.

To all whom it may concern:

Be it known that I, ARCHIE W. STEELE, a subject of the King of Great Britain, residing at 10 Park Avenue, Bloomfield, in the county of Essex, State of New Jersey, have invented certain new and useful Improvements in Electric Fuses; and I do hereby declare the following to be a full, clear, and exact description of the invention, such as will enable others skilled in the art to which it appertains to make and use the same.

This invention relates to electric fuses and is directed to the provision of a fuse of an improved construction which may be manufactured at low cost and which is more effective than fuses of low cost as heretofore constructed in suppressing the arc which is formed when a fuse is ruptured.

I have found that the danger of explosion and the emission of flame when a fusible link is ruptured may be greatly reduced by enclosing the central attenuated portion of the fusible link in a casing of insulating material which is filled with an absorbent substance such as plaster of Paris, particularly when the casing is provided with a plurality of transverse partition walls through which the fusible link extends, and by mounting the fusible link with its enclosing casing within a tube of insulating material having caps at its ends which are provided with slots through which the ends of the fusible link extend and upon which the ends of the link are secured by suitable screws.

The construction of this type which I prefer to employ is illustrated in the drawings annexed hereto in which Fig. 1 is a central longitudinal section of the fuse; Fig. 2 is a similar view, the plane of the section being at right angles to that of Fig. 1 on line 2—2 of Fig. 1; Fig. 3 is an end view of the fuse; Fig. 4 is a transverse section on line 4—4 of Fig. 2; Fig. 5 is a view partly in elevation and partly in section of the link with its surrounding casing; Fig. 6 is a view corresponding to Fig. 1 illustrating a modified construction; Fig. 7 is an end view of the construction shown in Fig. 6 and Fig. 8 is a view corresponding to Fig. 7 with the attaching screw removed.

Referring to these drawings, the fusible link is preferably in the form of a flat strip 9 which is reduced in cross-sectional area at the middle. The major portion of the

length of this fusible link is enclosed within a shell or casing 10 preferably made of paper which is curled to form a cylinder. At the ends and at points intermediate the ends of this shell 10 are partition walls 11 extending across the shell 10 and each of these partition walls is provided with a slot corresponding in size to the cross-section of the link 9. The entire shell 10 is filled with an absorbent material 12, preferably plaster of Paris. Such a fusible link with its enclosing casing may be manufactured in quantity at low cost by winding the tubes 10 and loading them from one end with first a partition wall and then a charge of plaster of Paris, the partition walls being held in position if desired by a suitable varnish and if desired the entire shell 10 may be coated with zinc chlorate or a similar substance which makes it less inflammable.

The link with its enclosing casing constructed as indicated in Fig. 5 is mounted within a tube 13 of insulating material such as fiber. The ends of this tube 13 are closed by end caps 14 preferably formed from sheet metal. These end caps and the coacting walls of the tube 13 are not threaded; instead the caps have a sliding fit upon the ends of the tube 13 but when they are in position upon the ends of the tube they are held against rotation in any suitable manner as by the provision of a pin 15 on each end cap extending inwardly and entering a slot 16 in the end of the tube 13.

The transverse walls of the end caps are provided with slots through which the ends of the fusible link 9 extend and these projecting ends of the link are bent over upon the transverse walls of the end caps. Adjacent to the slot through which the ends of the link 9 extends is a threaded hole adapted to receive the threaded shank of a screw 17 whose head overlies the end of the link so as to hold the link in position as is shown in Figs. 1 and 3. The ends of the link projecting beyond the heads of the screws 17 may have figures stamped on them to indicate the current carrying capacity of the fuse. Preferably the end caps are formed as indicated in Figs. 1 and 2 with the central portions of the transverse walls thereof sunk below the rim portions so that the heads of the screws 17 do not project beyond the planes of the rims.

With such a construction, removal of a

burned out link and substitution of a new one may be quickly effected, employing for the purpose no tool other than a screwdriver. It is only necessary to loosen the 5 screws 17, remove the end caps 14 by a sliding movement and then take out the link unit with its casing 10; a new link unit with its casing may then be inserted within the tube 13, the end caps 14 replaced with the 10 ends of the link 9 extending through the slots therein, the ends bent over and the screws 17 tightened upon them.

Figs. 6, 7 and 8 illustrate a slightly modified construction. In this form the screws 15 for securing the ends of the fusible link are in the form of threaded plugs 18 which fill the entire space within the countersunk ends of the end caps 19. The flanges at the edges of the end caps may be slotted as 20 shown at 20, so that when the ends of the

link 9 are bent over the transverse walls of the end caps, their ends will lie in these slots 20 as shown in Figs. 7 and 8 to disclose the figures stamped thereon.

I claim:

An electric fuse comprising the combination of a fusible link, a shell of insulating material surrounding the middle portion of the link, a filling within the shell, a rigid insulating tube enclosing the shell and in 30 close engagement with the wall thereof, end caps having a sliding fit upon the ends of the tube, screws entering threaded holes in the end caps and having their heads engaging the bent-over ends of the link to 35 thereby hold the fuse in assembled relation, and means for preventing relative rotation of the caps and tube.

In testimony whereof I affix my signature.
ARCHIE W. STEELE.
